UNITED STATES PATENT OFFICE.

J. HENRY MORRISON AND EDWIN ALLEN, OF NORWICH, CONNECTICUT.

CUTTER-HEAD.

SPECIFICATION forming part of Letters Patent No. 293,494, dated February 12, 1884.

Application filed June 1, 1883. (No model.)

To all whom it may concern:

Be it known that we, J. HENRY MORRISON and EDWIN ALLEN, both of the city of Norwich, county of New London, and State of Connecticut, have invented certain new and useful Improvements in Cutter-Heads, which improvements are fully set forth and described in the following specification, reference being had to the accompanying drawings.

15 Our improvements relate to that class of cutter-heads in which, by a peculiar combination and arrangement of cutting-edges properly adjusted around a common center, one is enabled to turn irregular forms with great rapidity and accuracy.

Our immediate object is to produce a cutter-head which shall be strong in its parts, simple in construction, easily sharpened and balanced, and the parts of which may be 20 quickly and cheaply duplicated and adjusted if broken, lost or worn out, a cutter-head which in its entirety shall be capable of turning with the utmost nicety spools or analogous articles of wood which require one or more 25 diameters and regular or irregular profiles.

Our improved form of cutter is intended solely for wood turning and finishing, and is specially adapted for use in that class of lathes or machines in which the cutters revolve at a 30 high rate of speed, the wood to be formed or turned being properly secured and rotated one or more turns against the cutters by any suitable mechanism.

The accompanying drawings represent our 35 new form of cutter-head constructed for turning spools as commonly used for thread.

In the several figures like letters indicate like parts.

Figure 1 is an end view of our cutter-head, 40 showing the several forms of cutters in their respective places properly adjusted, and also shows the method of securing each rigidly in place. Fig. 2 is a side or edgewise view of parts of our device, showing the blank or form 45 to which the several cutters are secured. Fig. 3 is an end view of the blank before referred to, showing the cutters for forming the barrel of the spool secured in proper position around said blank. Fig. 4 is a detached view of our 50 rim-cutter, showing also the provision for ad-

justing the same. Fig. 5 is a detached view of one of our barrel-cutters.

Our cutter-head is constructed, preferably, in three principal removable sections, A, A', and B, as shown in Fig. 2, these three parts 55 being adapted to receive and support the other and smaller parts. We do not, however, confine ourselves to said sectional form, but may, if so desired, construct the blank B and side pieces, A A', of a single piece of steel. When 60 constructed in sections, as in Fig. 2, we are enabled to use for the blank B cast metal or any other suitable material, and as the said blank is not subject to any wear it may be supplied with a new set of cutters, when need- 55 ed, and used for an indefinite length of time.

The blank B is constructed with a central hole to receive the arbor or mandrel on or with which it rotates, its outer surface or edge being flattened on two or more sides to receive 70 the cutters which form the barrel of the spool. Fig. 3 shows said blank flattened on four sides, and having the barrel-cutters C in proper position.

The cutter C (see Fig. 5) is constructed of 75 flattened steel with a beveled cutting-edge, and slotted at its rear end to allow for proper adjustment. Each of the cutters C is secured to the blank B by one or more set-screws, e.

The side cutters in our device are two in 80 number, A A', constructed of steel and fastened to the blank B, one on each side. These pieces A A' are provided with holes centrally located and corresponding with the arbor-hole in blank B. The outer edge of A A' is 85 provided with obliquely-cut transverse cutting-edges or teeth beveled to produce the angle shown at h in the spool outlined in Fig. 2. These teeth or cutting-edges on A A' are not, however, continuous, but are broken at two 90 or more equidistant points to receive the rim-cutters E, and also to allow the chips or dust to find a convenient exit in the act of cutting or turning. The office of the rim-cutters E is to form the outer edges or rims of the spool, 95 and in order to locate them the proper distance from the side of the blank B we interpose between them and B washers k, of suitable thickness to accomplish the desired result. The cutter E, with its individual washer, 100

is secured to B by a set-screw, a. It (E) is also provided with a slot, c, to allow for proper adjustment. This slot is an important feature of our invention, as without it it would be 5 impossible to bring the cutting-edge of E to its proper position relative to the several other cutters after the cutter E had been once removed and sharpened.

As our device is intended to revolve at a 10 high rate of speed, it is essential that it be carefully balanced, not only to avoid all vibration and jar of machinery, but also to allow each individual cutter to perform its share of the work.

15 Inasmuch as our several cutters are secured to the blank B by screws at various points near its outer edge, we find it very convenient to make use of small metal washers placed under the heads of one or more screws, (see

m, Fig. 1.) By this novel and inexpensive 20 method of balancing we are able to change the washers from screw to screw until the desired object is attained.

Having thus described our invention, we claim—

25 In combination with the blank B, the side cutters, A A', (broken to receive the rim-cutters and washers,) two or more rim-cutters, E, each provided with the slot c, the washers k, and the barrel-cutters C, all of said cutters being 30 secured to the blank B, as described, and for the purpose specified.

J. HENRY MORRISON.
EDWIN ALLEN.
